GUN MOUNTING

Lewis Motley, London, England, assignor to the
United States of America as represented by the
Secretary of the Army

Application December 29, 1942, Serial No. 470,505
In Great Britain October 12, 1939

Section 1, Public Law 690, August 8, 1946
Patent expires October 12, 1959

6 Claims. (Cl. 89—37)

1

This invention relates to gun mountings, and refers more particularly to those arrangements, normally intended for use against aircraft, in which the gun (or guns) proper—usually a machine gun or automatic rifle—is (or are) mounted on a supporting part which is pivoted to enable the gun (or guns) to be swung for both traverse and elevation. An example of such a gun mounting is described in my prior Patent No. 2,228,179.

It is sometimes desirable that a gun (or guns) on a mounting of this type should be capable of being employed against ground forces which might, in some cases, as for example when the gun mounting is carried on a lorry, be at a lower level than the gun (or guns). If it were attempted to depress the gun (or guns) on such ground forces by swinging the supporting part sufficiently far down, the axis of the gun (or guns) might be at such a low level both that sighting by the gunner would be inconvenient and that near objects such as a part of the lorry would intervene between the gun (or guns) and the target. It is the object of the present invention to provide a gun mounting which may be employed in this way without the aforesaid difficulties, and the invention consists broadly in the arrangement that the axis of said gun (or guns) proper may be tilted downwardly from the normal position relative to said supporting part while remaining at a higher level than if tilted to the same angle by the downward pivotal movement of said supporting part.

In order that the invention may be the more clearly understood, I will now describe two embodiments thereof as applied to the gun supporting part or gun arm of a gun mounting which in other respects is the same as that described in my prior Patent No. 2,228,179 aforesaid. In the following description reference will be made to the accompanying drawings, wherein:

Figure 1 is a side elevation of such a gun arm, having associated means according to the invention for mounting thereon a single Bren gun, said gun being shown in its normal position relative to said gun arm in full lines, and in a downwardly tilted position relative to said gun arm in chain dotted lines.

Figure 2 is a plan of said gun arm and associated means.

Figure 3 is an end elevation of the same looking from the direction of the arrow III of Figure 2.

Figure 4 is a side elevation showing a similar gun arm, having associated means according to the invention for mounting thereon two Bren

2

guns, the guns being in the normal position relative to the gun arm.

Figure 5 is a plan of the same with certain parts omitted for clearness.

Figure 6 is a side elevation of the same with the guns in a downwardly tilted position relative to said gun arm.

Referring first to Figures 1 to 3 the gun arm 1 is equivalent to the gun arm 14 of said prior Patent No. 2,228,179 and is mounted in the same way so as to be capable of swinging both for elevation and traverse about axes at the rear of the rotatable gunner's seat. In the drawings this gun arm is shown broken off at the rear end near these swing axes, and the remainder of the gun mounting which may be identical with that described in said prior specification is not shown.

The fixtures for supporting the gun fore and aft from this gun arm 1 comprise respective short supporting arms 2 and 3 each pivotally mounted at one end on said gun arm 1 so as to turn about horizontal transverse axes X—X and Y—Y, and terminating at the other end in the required standard fitting for attachment to the particular type of gun being employed (in the present case a Bren gun). The rear supporting arm 2 is considerably longer than the fore supporting arm 3 and, in the normal state—that is when the gun is to be used for its normal anti-aircraft purposes—the supporting arms may be arranged as shown with the front supporting arm 3 inclined a little rearwardly of the vertical and the rear supporting arm 2 inclined rearwardly nearly to the horizontal. With this arrangement the gun will be supported in a position more or less parallel to the gun arm which may be the most convenient position for normal use.

If the lorry carrying the gun mounting should be subject to a ground attack which it is desired to repel by means of the gun, it would be difficult or impossible to do this with the gun mounted on the gun arm 1 in the normal way just described because, if the gun arm 1 were lowered to the necessary angle the sighting by the gunner would be inconvenient and a part of the lorry might intervene between the gun and its target, but by simply pushing the gun forwardly, the rear supporting arm 2 turns to the vertical position and the front supporting arm is inclined forwardly. The gun is now directed downwardly relative to the gun arm 1 and may be easily depressed on the ground forces by the operation of said gun arm, since the axis of the gun is now much higher than if it were brought to the same angle by movement

of the gun arm 1 with the gun in its normal position relative thereto.

It will thus be seen that in general the gun may be adjusted to any required angle with respect to the gun arm, and, in particular, it may be adapted very rapidly for use against ground forces.

The supporting arms 2 and 3 are adapted to be locked against turning by screwing up a hand wheel 4 and a nut 5 respectively, and these are loosened when it is wished to adjust the gun.

The supporting arms 2 and 3 are of adjustable length each consisting of telescoping parts and means for locking them at an adjusted relative position. Thus, the arm 2 consists of a tubular portion 2a and a portion 2b adapted to slide longitudinally within it, the portion 2a being longitudinally slit and a nut 6 being provided to tighten and loosen said portion 2a on the portion 2b. In like manner the arm 3 consists of a tubular portion 3a, a portion 3b sliding within it and a nut and bolt clamp 7 for tightening and loosening said portion 3a on said portion 3b.

In construction, the pivotal mounting of the supporting arms 2 and 3 on the gun arm 1 is effected by providing respective bearing pins 8 and 9 projecting transversely and horizontally from said gun arm and pivoting the ends of said supporting arms on said bearing pins. To this end the portions 2a and 3a of said supporting arms are provided with split bearing bosses 2c and 3c which surround the bearing pins 8 and 9, and are adapted to be tightened and loosened thereon by means of the hand wheel 4 and nut 5 respectively.

As in the prior specification aforesaid the gun arm 1 is of adjustable length consisting of two telescoping parts 1a and 1b, the rear part 1b being the inner part and the front part 1a the outer part. In the present arrangements these two telescoping parts instead of being of circular section tubing as in said prior specification, are of square section tubing with rounded corners so that they cannot turn relative to each other.

Both the bearing pins 8 and 9 are mounted on the front part 1a. The front bearing pin 9 is permanently and rigidly secured to said front part 1a. The rear bearing pin 8 is permanently and rigidly secured to a tubular bush 10 which is of the same square section as said part 1a and is mounted on the rear end thereof. Both said tubular bush 10 and the rear end of the front part 1a, but not the rear part 1b, are slotted to enable them to expand and contract, and the tubular bush 10 is provided with a tightening hand wheel 11 whereby it may be tightened or loosened on the front part 1a, thereby tightening or loosening said front part on the rear part 1b.

The fittings mounted on the ends of the supporting arms 2 and 3 for attachment to the gun, are, in the example illustrated, those for a Bren type of gun, consisting simply of flattened end portions with eyelet holes in them. A Bren gun duly mounted on these fittings is shown in Figure 1 in full lines in the normal position. The position of the gun is indicated in chain dotted lines in the downwardly directed position.

The reference 12 designates a handle for swinging the gun arm.

Referring now to Figures 4 to 6, the gun arm 13 is again equivalent to the gun arm 14 of said prior Patent No. 2,228,179 except that, in this case said gun arm is shown as constituted by a single piece and not two telescoping parts.

The gun mounting is, in this case, for two

guns. The fixtures for supporting the two guns fore and aft from this gun arm 13 comprise a pair of equal short supporting arms 14 rigidly mounted parallel to each other on a common horizontal transverse shaft 15 which is rotatably mounted on said gun arm 13 near the forward end, and a pair of equal short supporting arms 16 rigidly mounted parallel to each other on a common horizontal transverse shaft 17 which is rotatably mounted on said gun arm 13 further towards the rear. These short supporting arms 14 and 16 each terminate at their free ends in the required standard fitting for pivotal attachment to the complementary fitting of the particular type of gun being employed, in the present instance a Bren gun. The two supporting arms 14 are adapted to be attached to the forward fittings of the respective guns and the two supporting arms 16 on to the rear fittings of the respective guns.

The rear supporting arms 16 are considerably longer than the forward supporting arms 14, and in the normal state—that is when the guns are to be used for their normal anti-aircraft purposes—the two supporting arm units may be arranged as shown in Figure 4 with the forward supporting arms 14 inclined a little rearwardly of the vertical and the rear supporting arms 16 inclined rearwardly nearly to the horizontal. With this arrangement the guns will be supported as indicated in dotted lines in Figure 4, in a position slightly upwardly inclined with respect to the gun arm 13.

When it is desired to attack ground forces the guns are simply pushed forwardly so that the rear supporting arms 16 turn to a position approaching the vertical and the front supporting arm is inclined forwardly towards the horizontal as indicated in Figure 6. The guns are now directed downwardly relative to the gun arm 13 and may be easily depressed on the ground forces, since the axes of the guns are now much higher than if they were brought to the same angle by movement of the gun arm 13.

When the guns are tilted at their rear position illustrated in Figure 4, the gravity bias tends to tilt them still further rearwardly and they are retained at said rear position by means of a stop in the form of a lug 18 projecting rigidly from the forward shaft 15 and having its end bent over as shown so as to abut against the arm 13 when the guns reach the rear position. In like manner when the guns are tilted at their forward position illustrated in Figure 6, their gravity bias tends to tilt them still further forwardly and they are retained at said forward position by means of a stop in the form of a lug 19 projecting rigidly from the rear shaft 17 and having its end bent over as shown so as to abut against the arm 13 when the guns reach their forward position. Thus, when changing to and from the two positions, all that is necessary is to push the guns forwardly or pull them rearwardly as the case may be, until they come to rest at the position determined by the abutment of the lug 19 or 18 against the arm 13.

Actually to secure the guns the more securely at their two positions, a hand wheel 20 is provided whereby the rear shaft 17 can be clamped in its bearing, but in cases where great speed of action is necessary the guns could be used, at least in the rear position where the recoil would aid gravity, without this wheel 20 being tightened.

The two guns are provided with common sights viz. a fore sight 21 and a rear sight 22 and these

are mounted on a sight bar 23 which is mounted on the gun arm 13 and is adapted to tilt relatively thereto in unison with the guns so that, at either position of the guns, the common sights are operative. This sight bar 23 is mounted on the gun arm in substantially the same way as each of the two guns. Thus an additional forward short supporting arm is mounted on the forward shaft 15 parallel and equal to the arms 14, and an additional rear short supporting arm is mounted on the rear shaft 17 parallel and equal to the arms 16. Actually these additional short supporting arms are not seen in any figure of the drawings. In Figures 4 and 6 they are concealed behind the arms 14 and 16, and in Figure 5 they are concealed beneath the sight bar 23. At their free ends, these additional short supporting arms are pivotally connected to the lower ends of lugs 24 and 25 rigidly secured to, and extending downwardly from, the sight bar 23. Thus the sight bar 23 will be tilted in unison with the guns as the latter are moved to and from their two positions and the sights will be operative for both positions.

Each of the short supporting arms 14 and 15, and each of the additional short supporting arms for the sight bar (which are substantially identical with the short supporting arms 14 and 15), are of adjustable length and may be angularly adjusted about its respective shaft. Such adjustments of length and angle of said short supporting arms are only effected during erection of the gun mounting in order to fit said arms properly to the guns and sight bar, and ensure that all the front supporting arms on the one hand, and all the rear supporting arms on the other hand, are of the same length and parallel.

Thus as clearly shown in the drawing each short supporting arm comprises two portions which telescope one within the other. The portion which is mounted on the shaft takes the form of a tube having a longitudinal slit 26 at its extremity and the other portion takes the form of a rod which is embraced by, and projects from, said tube. The rod portion is clamped at the adjusted position relative to the tube portion by drawing together, by means of a bolt 27, two lugs 28 which project from the tube portion on either side of the slit 26. Each tube portion is mounted on the respective shaft by means of a transverse tubular slit boss 29 in which said tube portion terminates and which encloses said shaft. This boss 29 is clamped onto the shaft by drawing together, by means of a bolt 30, two lugs 31 which project from said boss on either side of the slit. Obviously this admits of the angular adjustment of the short supporting arm on the shaft.

Dealing now with other structural details, the front shaft 15 bears in a bearing 32 rigidly mounted above the gun arm 13 and the rear shaft 17 bears in a similar bearing (not seen) rigidly mounted below said gun arm 13. This latter bearing is slit and is provided with lugs on each side of the slit (one of which is seen at 33) and said rear shaft 17 can be clamped against rotation, as heretofore stated, by drawing said two lugs together by means of a bolt on said hand wheel 20.

The angular position of the lugs 18 and 19 on the shafts 15 and 17 is also capable of adjustment so that the two positions of the guns may be pre-adjusted. To this end the lugs are mounted on the shafts in substantially the same man-

ner as the short supporting arms and no further description is deemed necessary.

What I claim and desire to secure by Letters Patent is:

5. 1. In a gun mounting, the combination with a pivotal main gun-supporting part which is movable about an axis located a substantial distance behind the gun for both traverse and elevation of a gun, of adjustable gun orienting means intermediate the gun and the main supporting part aforesaid for adjusting the elevation of the gun relative to said supporting part independently of the gun-elevating movement of said main supporting part, said orienting means comprising a 15 pair of arms pivotally mounted on the main gun-supporting part in spaced relation to each other in a fore and aft direction relative to the latter, with their respective pivotal axes disposed transversely to said main gun-supporting part, the 20 rearward arm being of greater length than the forward arm and each arm also having means for pivotally connecting the same to the gun at spaced intervals fore and aft of the latter, and said arms being conjointly movable in forward 25 and rearward directions for changing the position of the gun relative to said supporting part, from a position suitable for normal firing to a position forward of and at a greater downward inclination than said first-named position, and vice 30 versa, without changing the position of the main gun-supporting part.
2. In a gun mounting, the combination with a pivotal main gun-supporting part which is movable about an axis located a substantial distance 35 behind the gun for both traverse and elevation of a gun, of adjustable gun orienting means intermediate the gun and the main supporting part aforesaid for adjusting the elevation of the gun relative to said supporting part independently of 40 the gun-elevating movement of said main supporting part, said orienting means comprising a pair of arms pivotally mounted on the main gun-supporting part in spaced relation to the latter, with their respective pivotal axes disposed 45 transversely to said gun-supporting part, at least one of said arms being composed of adjustable telescopic parts and including means for locking said telescopic parts in adjusted positions of variable length, and each arm also having means 50 for pivotally connecting the same to the gun at spaced intervals fore and aft of the latter, and said arms being conjointly movable in forward and rearward directions for changing the position of the gun relative to said supporting part, from 55 a position suitable for normal firing to a position forward of and at a greater downward inclination than said first-named position, and vice versa, without changing the position of the main gun-supporting part.
3. In a gun mounting, the combination with a pivotal main gun-supporting part adapted to support a plurality of guns, said supporting part being movable for both traverse and elevation of the guns, of adjustable gun orienting means 60 intermediate the main supporting part aforesaid and the respective guns for simultaneously adjusting the elevation of the guns independently of the gun elevating movement of the main supporting part, said orienting means comprising a 65 pair of shafts rotatably mounted on the main gun-supporting part in spaced relation to each other in a fore and aft direction and with their respective axes of rotation disposed transversely to the main gun supporting-part, a pair of arms 70 connecting the respective shafts with each gun 75

and the rearward arms being of greater length than the forward arms, said arms being rigidly attached to the shafts at one end for pivotal movement about the axes of rotation of the shafts in a forward and rearward direction, and said arms being pivotally attached to the respective guns at their other ends and disposing said guns in their normal firing positions when the arms are shifted rearwardly, while inherently disposing the respective guns in downwardly inclined firing positions when the arms are shifted forwardly.

4. In a gun mounting, the combination with a pivotal main gun-supporting part adapted to support a plurality of guns, said supporting part being movable for both traverse and elevation of the guns, of adjustable gun orienting means intermediate the main supporting part aforesaid and the respective guns for simultaneously adjusting the elevation of the guns independently of the gun elevating movement of the main supporting part, said orienting means comprising a pair of shafts rotatably mounted on the main gun-supporting part in spaced relation to each other in a fore and aft direction and with their respective axes of rotation disposed transversely to the main gun-supporting part, a pair of arms connecting the respective shafts with each gun, said arms being rigidly attached to the shafts at one end for pivotal movement about the axes of rotation of the shafts in a forward and rearward direction, said arms also being pivotally attached to the respective guns at their other ends and disposing said guns in their normal firing positions when the arms are shifted rearwardly, while inherently disposing the respective guns in downwardly inclined firing positions when the arms are shifted forwardly, and se-

lectively operable means for releasably restraining at least one of said shafts against rotation.

5. A gun mounting as defined in claim 3, wherein the arms connecting the respective guns to the main gun-supporting part include means for adjustably varying the length of the respective arms.

6. A gun mounting as defined in claim 3, wherein means is provided for angularly adjusting the respective arms on their respective shafts.
